UNITED STATES PATENT OFFICE

JOSEPH HIDY JAMES, OF PITTSBURGH, PENNSYLVANIA, ASSIGNOR TO CLARENCE P. BYRNES, TRUSTEE, OF SEWICKLEY, PENNSYLVANIA

TREATING PARTIAL OXIDATION PRODUCTS

No Drawing. Original application filed May 18, 1923, Serial No. 639,986. Divided and this application filed June 19, 1928. Serial No. 372,218.

This application is a division of my co-pending application Serial No. 639,986, now Patent No. 1,721,959 of July 23, 1929.

The present divisional application relates 5 to fractioning a partial oxidation product containing oxygen derivatives of aliphatic hydrocarbons, separating the fractions and further oxidizing a fraction or a portion of a fraction thus separated; and to further 10 processes not claimed in and divisible from my Patent No. 1,721,959.

In my copending applications Serial No. 272,567, filed January 22, 1919; Serial No. 435,355, filed January 6, 1921, and others, I 15 have described methods for the vapor phase partial oxidation of hydrocarbons, including petroleum, shale oil, the low temperature distillation of coal and the like, consisting mainly of aliphatic hydrocarbons.

20 In such methods, the liquid hydrocarbons are vaporized, mixed with a regulated proportion of oxygen, usually in the form of air, and then passed through a hot conversion zone at a temperature ranging between 270°

25 C. and 500° C., depending upon the products whose preponderance is desired. In the hot conversion zone, the vapor mixture is preferably subjected to contact with catalytic material consisting of the oxides or compounds

30 of high-melting point low-atomic volume metals. These metals appear on the Lothar Meyer diagram of the periodic series beginning on the descending side of the third peak, descending side of the fourth peak and the 35 descending side of further peaks developed since the date of this diagram. The class includes the following metals:—titanium, vanadium, chromium, manganese, zirconium, niobium, molybdenum, tantalum, tungsten 40 and uranium.

As set forth in my copending application, Serial No. 435,355, the vapor mixture may be and preferably is passed over a plurality of layers, air or oxygen being supplied between 45 some or all of the layers. The air proportion

is varied according to the catalyst used, the temperature and the speed of the current. The more active the catalyst, the nearer the air can approach the theoretical amount; and the same as to temperature. Steam may also 50 be supplied in regulated proportions. The temperature is below that of continuous self-sustained combustion and will vary according to the hydrocarbon treated, the catalyst used, etc.; and if a predominance of aldehyde is desired, will usually be lower than that where a predominance of aldehyde fatty acids is desired.

The condensed product of this treatment 55 will contain alcohols, aldehydes, and oxy- 60 genated acids in varying proportions, depending upon the conditions of the process, the hydrocarbon treated, etc. As the liquid hydrocarbon treated contains hydrocarbons of varying molecular weight, the product 65 will contain alcohols, aldehydes and acids of varying molecular weights. The aldehydes are probably in part monoaldehydes and in part dialdehydes.

70 My present invention is designed to further treat such product of my main process and to further oxidize the constituents thereof, or portions of them, to give a better type or class of products for industrial uses, such as soap making, etc. When the original product is 75 saponified in the ordinary way, the soaps produced are dark in color and have a peculiar odor. The color and odor are both greatly improved by the further oxidation treatment of my present invention. This application is 80 in part a continuation of my copending application, Serial No. 281,124, filed March 7, 1919 now Patent No. 1,697,653 of January 1, 1929.

85 The acids of my main process, particularly in the higher boiling ranges, are aldehydic in character and the "congeneric oil" (the non-saponifiable oil) of the product consists almost completely of bodies containing oxy- 90 gen. Hence the condensed product is amen.

able to further oxidation which my present invention is designed to accomplish.

Under the preferred form of my present process, I propose to oxidize the oxygenated acids of varying molecular weights to dibasic acids, and the aldehydes of varying molecular weights to ordinary monobasic fatty acids or to dibasic acids (depending upon whether the aldehyde is a mono- or a di-aldehyde). If the reaction is continued sufficiently long, the alcohols may also be oxidized to monobasic or dibasic acids.

This further second oxidation step may be applied to the entire condensed product of my original or main partial oxidation process, or to any fraction thereof. I prefer in practice to distil off the lower boiling point fractions and apply the further oxidation to the remainder. Thus I prefer to distil off those portions of the original condensed product distilling under 200° C. and apply the further process to the remainder. In some cases, I may distil up to 300° C. or higher and use the remainder for further oxidation.

The further oxidation may be carried out in several ways and I may use "chemical" oxidation methods, such for example as set forth in the following three examples:

30 I. This is the chromic acid oxidation and may be carried out by the use of a solvent (for both the product and the chromic acid) or without such solvent. In the latter case, a suspension of the organic product, and a water solution of the chromic acid, is used.

An example of the suspension method is as follows: A sample consisting of 100 c. c. of the entire condensed oxidation product made by the catalytic air oxidation of unrefined spindle oil (mid-continent), and containing approximately 30% of organic acids, was treated in a suspension of one to four sulphuric acid with a half saturated solution of chromic acid in water. The suspension of oil oxidation product was maintained by violent mechanical agitation and the chromic acid solution was run in slowly, care being taken that the temperature did not rise above 40° C. After the chromic treatment, when a

50 test for free chromic acid was obtained which persisted for one hour, the reaction was stopped, the organic product separated, washed and tested for the quality and amount of fatty acids. It was found that the fatty acids had risen from 30% to 48%, and that only a very small amount of aldehydic substances were left. The soaps, even when made by boiling with caustic potash or caustic soda solution were of a yellowish cream 55 color, in strong contrast to the dark brown soaps formed by the original "catalytic oxidation" acids.

In another trial with the same catalytic oxidation product, but by the use of 200 c. c. 60 of glacial acetic acid as a solvent and a chro-

mic acid solution made by mixing one volume of a saturated water solution of chromic acid with four volumes of glacial acetic acid, and a temperature of 27 to 32° C., the other conditions as to agitation, addition of oxidant, etc., being the same as in the preceding example, the acid content was brought up to 59% and the acids were of even better quality than those obtained in the foregoing experiment.

70 For large scale operation, the first or suspension method will probably prove more economical. Since it is not at all difficult to work a cyclic electrolytic regeneration recovery process for the chromic acid, this method of making fatty acids has great possibilities.

75 II. This method of carrying out the chemical oxidation of the product obtained by the first or catalytic oxidation is based on the oxidizing action of chlorine, and further, on the direction of hypochlorous acid decomposition towards the formation of hydrochloric acid and oxygen.

80 When chlorine gas is passed into water, hypochlorous acid (HOCl) is one of the products.

85 However this mixture of products on the right hand side of the equation can react to reform the original substances, chlorine and water. In the presence of certain catalysts, the hypochlorous acid (HOCl) can be made to decompose as follows:

90 This reaction applied to calcium hypochlorite in water solution is the well known "La Voisite" process for making oxygen.

95 I have applied this reaction to a water or dilute acid suspension of the catalytic oxidation mixture to accomplish the same purpose as that of Method I.

100 The following example will show how this reaction is applied.

A mixture was made of the following proportions: 100 c. c. spindle oil catalytic oxide mixture, 500 c. c. water, 100 c. c. 2% cobalt chloride solution, and 50 c. c. concentrated hydrochloric acid solution.

110 A vigorous mechanical stirring brought about a good suspension of the oxidized oil in the water solution. A slow stream of chlorine gas was passed into the suspension for six hours at 95° C. Some cobalt soaps separated out under these conditions. While the character of the acids recovered from this mixture was not as good as in Method I, the acid has been increased to approximately 50%, (some aldehyde bodies were still present or had been formed because of incomplete oxidation). This method can be easily used to increase the acid content of a catalytic air oxidation mixture, since the chlorine is 115 available and cheap.

120 III. This method is based on the proper-

ties, physical and chemical, of the oxides of nitrogen and of nitric and nitrous acids. Nitric acid itself is a violent oxidizing agent. The oxides of nitrogen, nitric oxide (NO), 5 nitrogen dioxide (NO₂) are soluble in nitric acid and in nitric acid water solutions down to certain concentrations. Nitric acid readily breaks down, these oxides being the main products. Now the lower of these oxides 10 (NO) readily takes on oxygen from the air going up to the dioxide (NO₂). The dioxide is an energetic oxidizing agent.

Having, as a medium, dilute nitric acid to act as a solvent for these oxides and also to 15 provide a menstruum for the suspension of the organic material to be oxidized, we have all the conditions for what is really an air oxidation of the catalytic oxidation mixture. The nitric acid and the nitrogen oxides function 20 about the same as they do in the lead chamber process for making sulphuric acid.

This method, then, consists in making a suspension of the organic material in the nitric acid solution of whatever concentration selected and at temperatures usually rather low for the best results; then by bubbling air through the agitated suspension, the desired oxidation can be carried almost to completion.

The following example will serve to illustrate the application of this method. A mixture was made up of the following proportions: 300 c. c. catalytic oxidation mixture made from a 50:50 gas oil-wax distillate blend and 500 c. c. nitric acid solution, 22%.

35 This mixture was violently agitated by a mechanical stirring device and air bubbled in violently for twelve hours, the temperature not being allowed to rise above 50° C., being kept most of the time at 45° C. The oxidation 40 mixture gradually changed in color from the original dark brown to a light brick red. When the oxidation is complete, the greater part of the organic acids will sink in water. In this example, the bottom layer, representing 45 80% of the total, was completely saponifiable and the top layer, representing 20% of the product, was 80% saponifiable. This shows that practically 96% of the material fed into the original catalytic air oxidizer 50 had been acted on by the oxidation, as the action on the original hydrocarbons under these mild oxidizing conditions is very slight.

I propose to carry out this reaction on a large scale by blowing air successively 55 through a long connected series of such mixtures in properly arranged apparatus. The small amount of nitrogen oxides escaping from the last vessel of the train can be easily absorbed in an alkali tower and the tartric 60 and nitrous acids recovered; or the Gay-Lussac tower method used by the manufacturers of sulphuric acid may be used for this recovery.

I may also add certain oxides to the acid 65 in order to aid in the above reaction, such

as vanadium pentoxide, molybdenum trioxide, etc.

In all the above methods, it should be noted that a good total recovery is obtained— 70 from 85 to 95% being the usual practice.

I may also in each of the foregoing methods remove the last of the aldehydic bodies at the end of the "second" oxidation by long agitation of the suspended acids in a rather concentrated sodium bisulphite solution. 75

Final purification of the ordinary vacuum or vacuum-steam distillation methods may be applied to the products made by any of the above schemes.

While I may "chemically" oxidize the liquid partial oxidation or partial combustion product in the liquid phase, as above described in the typical methods set forth, I may, especially for certain purposes, vaporize said original partial oxidation products of my main process, mix the vapor with oxygen (preferably in the form of air) and subject the mixture to a catalytic partial oxidation, using steam also in some cases, as set forth in my copending application Serial No. 281,124, filed 80 March 7, 1919, now Patent No. 1,697,653 of January 1, 1929. In this step, which is generally the same as the main original process step, a catalyst may or may not be used, though I prefer to employ it in the hot reaction zone. In this step, the carbon compounds of the original product are further oxidized, the aldehydes being largely converted into acids. 85

The multiple-screen system of my copending application Serial No. 435,355 may be advantageously employed in this further oxidation step, and as in the original process, the air is regulated and the catalyst maintained within a definite range of temperature, 100 depending upon the average molecular weight of the mixture treated, which, in turn, depends upon the oil fraction treated in the main process. Here again, the temperature is preferably kept below that of continuous 105 self-sustained combustion, though such may occur and completely oxidize a part of the vapor mixture. This, however, lowers the yield. 110

The proportions of air and aldehyde vapor, 115 whether of the whole product or a fraction thereof, should be varied according to the particular catalyst used, the temperature employed and the speed of the current. The more active the catalyst, the nearer the proportion of air can approach the theoretical amount. The same is the case as to raising the temperature of the catalyst. The more active the catalyst or the higher the temperature, the nearer the proportion of air 120 may approach to the theoretical amount. With less active catalysts, or with a lower temperature, the greater is the proportion of air which should be used. 125

The catalysts used are preferably in the 130

same group as those used in the original process. The original process is preferably carried out to produce a predominance of aldehydes, the temperature being kept somewhat lower than that for producing aldehyde fatty acids, for example, around 250° C. for Pennsylvania kerosene.

I will now describe a specific example of my process using the above apparatus:

Conditions

(A) Catalyst: Uranyl molybdate on asbestos, held between parallel screens, the active material packed in a disk-shaped space 4 c. diameter and 1.25 c. thick.

(B) Aldehyde mixture treated: A mixture of aliphatic aldehydes made from Pennsylvania petroleum kerosene having the following composition:

	Per cent
Aliphatic aldehydes	81
Aldehyde fatty acids	10
Hydrocarbons (aliphatic)	9

(C) Air rate 1.2 liters per minute
 (D) Water flow 30 c. c. in 45 minutes
 (E) Aldehydes treated, 60 c. c. in 45 minutes
 (F) Temperature 300 to 330° C.

Results

49 c. c. of liquid product recovered which has the following analysis:

	Per cent
Aldehyde fatty acids	65
Aliphatic aldehydes	31.5
Hydrocarbons (aliphatic)	3.5

In addition, from the water-absorbing system, aldehyde fatty acids soluble in water are recovered in the form of their calcium salts, amounting to 2.64 grams.

In using this vapor phase oxidation method for the original products containing alcohol and aldehydes and aldehyde acids, the lighter portion or portions of the original product may be distilled off, before the further oxidation step is applied to the heavier portions.

The temperatures used in the oxidation steps vary from 230° C. to 500° C., depending upon the fraction originally treated, the amount of air, etc.

I consider myself the first to discover a practical process for treating mixtures of aliphatic aldehydes of varying molecular weight and converting them into the corresponding acids; and also the first to oxidize a mixture containing alcohols and aldehydes and convert portions of the aldehydes into acids.

In the "chemical" oxidation step, true fatty acids are produced along with dibasic acids. By the term "air" in my claims, I intend to cover air or oxygen or any gas mixture containing free oxygen.

A catalyst may or may not be used in the vapor phase oxidation step; the apparatus used may be widely varied, the chemical oxidant used may be changed and other changes may be made without departing from my invention.

Claims to the salts of dibasic acids and methods of making them are not included in this case as such are covered in my copending application Serial No. 549,567, filed April 4, 1922, for method of making dibasic acids and compounds thereof, now Patent No. 1,721,958 of July 23, 1929.

I claim:

1. The method of treating a partial oxidation mixture containing hydrocarbon oxygen derivatives of different molecular weights, consisting in fractioning the same into fractions of different average molecular weight, each containing oxygen derivatives of different molecular weights, separating the fractions and then further oxidizing a fraction or part thereof.

2. The method of treating a partial oxidation mixture containing hydrocarbon oxygen derivatives of different molecular weights, consisting in fractioning the same into fractions of different average molecular weight, each containing oxygen derivatives of different molecular weights, separating the fractions and then further oxidizing at least a portion of a fraction.

3. The method of treating a partial oxidation mixture containing hydrocarbon oxygen derivatives of different molecular weights, consisting in fractioning the same, separating the fractions and then further oxidizing at least a portion of a fraction by mixing the same with air and passing it through a hot reaction zone at a reactive temperature.

4. The method of treating a partial oxidation mixture containing hydrocarbon oxygen derivatives of different molecular weights, consisting in fractioning the same, separating the fractions, vaporizing at least a portion of a fraction, and mixing the same with an oxygen-containing gas and passing it through a hot reaction zone at a reactive temperature.

5. The method of treating a partial oxidation mixture containing hydrocarbon oxygen derivatives of different molecular weights, consisting in fractioning the same, separating the fractions and then further oxidizing at least a portion of a fraction by mixing the same with air and passing it through a hot reaction zone at a reactive temperature in the presence of a catalyst.

6. The method of treating a partial oxidation mixture containing hydrocarbon oxygen derivatives of different molecular weights, consisting in fractioning the same, separating the fractions, vaporizing at least a portion of a fraction, and mixing the same with an oxygen-containing gas and passing it

through a hot reaction zone at a reactive temperature in the presence of a catalyst.

7. In the treatment of a partial oxidation mixture containing hydrocarbon oxygen derivatives of different molecular weights, the steps consisting of fractioning the same into fractions of different average molecular weight, each containing oxygen derivatives of different molecular weights, separating the 10 fractions, and then further oxidizing at least a portion of a fraction by adding an oxidizing reagent thereto while in the liquid phase.

In testimony whereof I have hereunto set my hand.
